Application June 29, 1950, Serial No. 170,966

21 Claims. (Cl. 143—32)

1

The present invention relates to chain saws and particularly to chain saws driven by internal combustion engines.

In order to be used for cutting down trees and also for cutting up trees after they are felled, it is necessary for a chain saw to operate in a felling position with the saw chain in a horizontal plane and also in a bucking position with the saw chain in a vertical plane. Moreover, it is desirable for the saw to be able to tilt at least 30° in any direction from the normal felling and bucking positions.

The operation of the saw in these various positions gives rise to a number of problems. In the first place, there is a problem of supplying a proper fuel-air mixture to the engine since the carburetor of an internal combustion engine has to remain right side up to function properly. There is also the problem of getting fuel from the fuel tank to the carburetor in all positions of the saw and of preventing leakage of fuel through the vent hole that is normally provided in the filler cap of the fuel tank and is necessary in order to admit air as the fuel is used up. Manipulation of the saw to turn it from one position to another and to hold it in all cutting positions with minimum effort on the part of the operator, and hence with minimum fatigue, is a further related problem that arises from the need of operating the saw in different positions.

It has heretofore been proposed to mount the supporting plate for the cutting chain rotatably on the frame of the saw so that it can be turned through a 90° angle. This results in structural complications and also complicates the drive for transmitting power from the engine to the chain. It is also inconvenient since the operator must stop the saw, set it down, loosen the chain support, turn it to a new position, lock it in place, then start the saw and pick it up again.

It has also been proposed to mount the carburetor so it can be turned to one position when felling and another position when bucking. However, with the arrangements heretofore available, it has been exceedingly inconvenient to turn the carburetor and the saw at the same time while the saw is running. Difficulty has also been experienced in maintaining a constant supply of fuel from the fuel tank to the carburetor and engine in all positions of the saw. This is particularly true when the fuel tank is partly empty. Moreover, the arrangement of handles on the saw has made it inconvenient and awkward to turn the saw and to hold it in the different positions.

2

Another expedient that has been proposed is to use a pressure fuel system in conjunction with a fuel injection arrangement intended to work in any position of the saw. Such an arrangement has been found to be so complicated that it is difficult to keep in proper operating condition. As most lumbermen are not highly skilled mechanics, they cannot be relied on to service such equipment. A further objection arises from the fact that the fuel supply system does not work uniformly in all positions of the saw. There has hence never been a wholly satisfactory solution to the problem of operating a chain saw in all of the positions normally required for felling and bucking.

It is an object of the present invention to provide a chain saw of improved construction which will operate equally well in all cutting positions and which can be turned from one position to another quickly and easily without stopping the engine. In all positions of the saw, in accordance with the invention, the operator's hands are held naturally so that there is minimum strain and fatigue. In fact, the operator's hands are held in substantially the same position for both felling and bucking. In normal operation of the saw, the operator need never remove his hands from the handles.

Another object of the present invention is to provide a simplified fuel system in which a simple float type carburetor is used and fuel is fed by gravity from the fuel tank to the carburetor in all cutting positions of the saw. The fuel tank is divided into a plurality of interconnected compartments arranged in such manner that, even when the saw is tipped so that a major portion of the fuel tank is below the fuel outlet leading to the carburetor, sufficient fuel is trapped and held in the compartment with which the fuel line is connected to run the engine during its operation in this position. This is true even though the fuel tank may be nearly empty. There is no fuel pressure system or other complication. In conjunction with these features, the fuel tank is provided with a novel venting system which vents the tank while avoiding leakage of fuel despite the different positions to which the saw is turned and even with a full tank.

Other features, objects and advantages of the invention will appear from the following description and claims and from the accompanying drawings which show, by way of example, two embodiments of our invention. Certain features of the chain saw are more fully described in our

companion application Serial No. 167,596 filed June 12, 1950.

In the drawings:

Fig. 1 is a plan view of a chain saw in accordance with the invention, the saw being shown in bucking position. Only a portion of the chain support and cutting chain is shown.

Fig. 2 is a side elevation from the left hand side of the saw shown in Fig. 1.

Fig. 3 is a side elevation on a larger scale of 10 the right hand side of the saw with most of the chain support and chain omitted.

Fig. 4 is a vertical section through the fuel tank and the carburetor, the approximate location of the section being indicated by the line 15 4-4 in Fig. 1.

Fig. 5 is a rear view of the chain saw, certain portions being omitted and a portion of the fuel tank wall being broken away to show internal construction.

Fig. 6 is a horizontal section on a larger scale taken through the carburetor and associated parts, the position of the section being approximately on the line 6-6 in Fig. 4.

Fig. 7 is a side elevation of another embodiment of the invention, showing the right hand side of the saw.

Fig. 8 is a rear elevation of the chain saw shown in Fig. 7 with portions broken away to show interior structure in section.

Fig. 9 is a side elevation on a smaller scale showing the left hand side of the chain saw of Fig. 7.

The chain saw illustrated in Figs. 1 to 6 of the drawings comprises a frame or chassis, a chain support mounted in fixed position on the chassis, a cutting chain running on the chain support, an internal combustion engine, a power transmission system including an automatic clutch between the engine and a driving sprocket for the cutting chain, a fuel supply system for the engine including a fuel tank of novel construction, a carburetor mounted in a novel manner, a novel air intake assembly and an intake manifold and a novel arrangement of handles for holding and manipulating the chain saw, one of the handles being connected with the carburetor so as automatically to keep the carburetor upright when the saw is turned from felling to bucking position and vice versa, and a throttle control associated with the latter handle.

The frame or chassis 1 comprises the stationary portions of the chain saw on which other parts are mounted, the terms being used somewhat flexibly in that certain parts are at times referred to specifically and at other times are included in the generic designation of frame or chassis.

The chain support 2 is preferably in the form of a "beaver tail" shaped supporting plate of known type over which the cutting chain runs. It is mounted in fixed position on the chassis 1 in a vertical plane and with its central longitudinal axis at an angle to the horizontal, as seen in Fig. 2. For a two-man saw, the chain support is provided with a handle at its outer end. The handle is omitted or removed when the saw is to be used by a single operator. The cutting chain 3 comprises a flexible chain on which cutting teeth and rake teeth are provided and may be of known or suitable type. The outer edge of the chain support 2 is provided with a bearing surface over which the cutting chain runs.

The engine 4 is shown as a one-cylinder two-

cycle internal combustion engine having a horizontal cylinder 5, spark plug 6, crank shaft 7 and crank case 8. At its left hand end, as viewed from the rear of the saw, the crank shaft carries 5 a fly wheel and fan which are enclosed in an approximately circular fly wheel housing 9. A cable-type starter having a starting handle 10 (Fig. 2) is also provided at the left hand side of the saw.

Power from the engine is transmitted to a sprocket for driving the cutting chain 3 through a transmission including an automatic clutch which is shown and described in the above mentioned companion application. The transmission is disposed at the right hand side of the engine and is enclosed in a transmission housing 12 (Figs. 1 and 3). An arcuate series of points or teeth 13 provided on the transmission housing adjacent the base of the chain supporting plate 20 2 is adapted to engage the work and act as a fulcrum in feeding the cutting chain into the work.

The fuel system for the engine comprises a fuel tank 14, a carburetor 15 to which fuel is supplied from the tank by flexible tubing 16, an air intake assembly 17 (Fig. 5) for supplying air to the carburetor and an intake manifold 18 leading from the carburetor to the crank case of the engine.

30 The fuel tank 14 is approximately L-shaped in side view and comprises an upper main chamber 20 overlying the engine, and a lower auxiliary chamber 21 projecting downwardly from the rear portion of the main chamber. The tank 35 has side walls 22 and 23, an outer wall 24 which is approximately semi-circular and forms the top and the rear side of the tank and a bottom wall 25 comprising an approximately horizontal portion 26 which overlies the engine and forms the 40 bottom of the main chamber 20, a downwardly extending portion 27 which lies to the rear of the engine and forms the front wall of the auxiliary chamber 21 and a rearwardly extending portion 28 which joins the lower rear edge of the outer wall 24 and forms the bottom of the auxiliary chamber 21. The radius of the arcuate outer wall 24 is approximately the same as that of the fly wheel housing 9 so that the outlines of the fuel tank blend into those of the fly wheel housing. 45 As will be seen in Fig. 4, the fuel tank fits compactly over the engine. It also blends in with the transmission housing 12 to provide maximum compactness and neatness of appearance.

50 The main chamber 20 and auxiliary chamber 21 of the fuel tank are partially separated from one another by a partition or baffle 30 which is approximately horizontal and forms in effect a continuation of the horizontal portion 26 of the bottom wall 25 (Fig. 4). The partition 30 joins the bottom wall 25, the rearward portion of the outer wall 24 and the right side wall 23, with substantially fluid-tight joints but the left hand end of the partition is spaced a short distance 55 away from the left hand side wall 22 of the tank to provide a communicating opening 31 (Fig. 5) between the upper main chamber 20 and the lower auxiliary chamber 21.

60 The lower chamber 21 is divided by a partition or baffle 32 into two compartments 33 and 34. The partition 32 is approximately vertical and joins the partition 30 and portions 27 and 28 of the bottom wall 25 with substantially fluid-tight joints. The rear edge of the partition 32 65 is spaced a slight distance from the rearward

portion of the outer wall 25 so as to provide a communicating opening 35 (Fig. 1) between the two compartments 33 and 34. The partition 32 is located nearer the right hand side of the fuel tank, being spaced from the right hand end of the chamber 21 a distance equal to approximately one-third to one-fifth the width of the tank.

The fuel tank is provided with an outlet opening 36 which is located at the lower front right hand corner of the compartment 34 and preferably provided with a suitable shut-off valve. The flexible tube 16 (Fig. 3) leads from this outlet to the carburetor 15. The tank is also provided with a filling opening 37 located in the upper portion of the outer wall 34. The filling opening 37 is surrounded by a downwardly projecting skirt 38 (Figs. 4 and 5) and is provided with a removable filler cap 39. The removable closure 39 is liquid-tight and airtight and in this respect is unlike the usual filler cap which is provided with a small vent opening.

The venting of the fuel tank to admit air as the fuel is used up and thereby avoid the creation of a vacuum in the tank is provided by the arrangement of openings, cups and tubes illustrated in Figs. 1, 4 and 5. A vent cup 41 is provided on the upper portion of the outer wall of the fuel tank at the right hand side of the tank and preferably is slightly forward of the uppermost portion of the wall 24 when the saw is in the horizontal position illustrated in Fig. 4. A second vent cup 42 is provided on the outer wall near the left hand side of the tank and to the rear of the vent cup 41. As seen in Fig. 4, the vent cup 42 is disposed at an angle of approximately 45° from the cup 41 and is hence lower when the saw is in horizontal position. While the vent cups 41 and 42 are shown as being affixed to the inner surface of the outer wall of the tank with a fluid-tight joint, they may, if desired, be on the outside. The vent cup 41 is in communication with the atmosphere through a small vent hole 43 located in the rearward portion of the cup. The vent cup 42 communicates with the atmosphere through a small vent opening 44 located in the forward and upper portion of the cup.

A vent tube 45 extends rearwardly and toward the left from the vent cup 41 and terminates near the vent cup 42. As seen in Figs. 1, 4 and 5, the open end 46 of the tube 45 opens into the interior of the tank at a point adjacent the side wall of the cup and located above and to the left of the center of the cup. A vent tube 47 extends upwardly, forwardly and to the right from the vent cup 42 and terminates adjacent the vent cup 41. As illustrated in the drawings, the open end 48 of the vent tube 47 is located between the side wall of the vent cup 41 and the right side wall 23 of the tank. The vent tubes 45 and 47 follow the curvature of the outer wall of the tank and are shown affixed to the inner surface of the tank wall.

The arrangement of vent tubes, cups and openings described above has been found to provide proper venting of the tank in all of the operative positions of the saw without permitting leakage of fuel. The cups 41 and 42 provide storage space for receiving fuel which drains from the tubes 45 and 47 when the saw is tilted in certain positions. Otherwise, this fuel might escape through the openings 43 and 44. When the saw is tilted back in the opposite direction, the fuel drains from the vent cups back into the

tank. The arrangement is such that the open end of at least one of the vent tubes is always in the air space above the fuel in all operative positions of the saw.

The carburetor 15 is a float-type carburetor having a float chamber 50, an annular float 51, needle valve 52, a butterfly-type choke valve 53 located in an air inlet passage 54 and a similar throttle 55 located in an outlet passage 56 for the fuel-air mixture. To provide good idling characteristics, the carburetor also has an idling air valve 57 and mixing chamber 58 from which a fuel-air mixture is led to the engine through a passageway 59 and a flexible tube 60 when the engine is running at idling speed.

To operate properly, a float-type carburetor needs to be kept right side up. In accordance with the present invention, provision is made for maintaining the carburetor upright at all times while permitting the saw to be turned through an angle of 90° from bucking to felling position. For this purpose, the carburetor is rotatably mounted between the intake manifold 18 and the air intake assembly 17.

One end of the intake manifold 18 has a flange 62 by means of which the manifold is bolted to the engine. The other end of the manifold terminates in a circular portion 63 surrounded by an annular flange or shoulder 64 which is spaced from the end of the circular portion and provides a seat for a rubber ring 65 which is shown as being of substantially square cross-section. The term "rubber" is herein used to include natural or synthetic rubber-like compositions. An extension collar 66 which is bolted to the flanged end of the carburetor mixture outlet 56 surrounds the circular end portion 63 of the intake manifold and seats against the rubber ring 65, which provides a cushioned bearing for the carburetor.

At the opposite side, the carburetor is supported in a similar manner by a rear bracket assembly comprising the air intake and rear handle. The air intake assembly 17 includes an air filter unit 68 having a hollow cylindrical casing 69 which is open at both ends and a cylindrical filter unit 70 mounted inside the casing with an annular air passage 71 between the casing and the filter. Air enters the inside of the filter from both ends and flows through the filter into the annular passage 71. A rotatable and reciprocable brush 72 is provided for cleaning the inside of the filter.

The assembly is mounted on the chassis by a bracket portion 73 which is preferably integral with the filter casing and is secured to the chassis by two bolts 74 (Fig. 5). A tubular air passageway 75, which is shown integral with the bracket, projects laterally from the filter casing 69 and terminates in an integral sleeve bearing portion 76 which is open at both ends. The axis of the bearing portion 76 extends in a fore and aft direction, substantially in alignment with the circular end portion 63 of the intake manifold, and is thus approximately perpendicular to the air passageway 75. A bushing 77, preferably formed of a suitable bearing material such as bronze, fits inside the sleeve portion 76 and a fixed indexing plate 78 is provided on the rear end face of the sleeve portion.

A swivel member 80 is rotatable inside the bearing bushing 77 and has an annular flange 81 adjacent the indexing plate 78. An annular swivel plate 82 secured to the member 80, for example by a plurality of screws 83, bears on the

front end face of the bearing bracket 76 and thus cooperates with the flange 81 to hold the swivel member 80 against axial movement. The swivel plate 82 and adjacent end face of the swivel member 80 together form an annular recess to receive a rubber ring 85 which, as shown, is identical with ring 65 described above. The end of the air inlet passage 54 of the carburetor seats on the rubber ring 85 so that the carburetor is in effect clamped between the two rubber rings 65 and 85. The length of the carburetor is slightly greater than the free distance between the rings so that the rings are under compression when the parts are assembled and provide a cushion support protecting the carburetor from jars and vibration.

The swivel plate 82 has forwardly projecting cup-shaped ears 86 which loosely embrace correspondingly shaped protuberances 87 provided on opposite sides of the air inlet passage 54 of the carburetor. These ears cause the swivel member and carburetor to turn together and also prevent radial displacement of the adjacent end of the carburetor.

The bearing bushing 77 has a radial opening aligned with the air passageway 75 and the swivel member 80 has a passageway 88 comprising an axially extending portion 88a communicating with the air inlet of the carburetor and a radially extending portion 88b communicating with the passageway 75 so as to provide a continuous air passage from the annular space 71 surrounding the filter element 78 through the passageway 75 and the passage 88 of the swivel member 80 to the carburetor. The radial portion 88b of the passage 88 in the swivel member 80 is of sufficient circumferential extent to permit this member to rotate 90° without cutting off the air flow to the carburetor, being like passage 223 of the swivel member 230 shown in Fig. 8.

The swivel member 80 provides a rotatable support for a rear handle 90 which constitutes one of the handles for holding and manipulating the saw. The rear handle is approximately D-shaped comprising two arms 91 and 92 which curve rearwardly and away from one another and a horizontal tubular handgrip portion 93 extending across between the rear ends of the arms. The swivel member, arms and hand grip are preferably integral with one another. The left arm 91 is longer than the right so that the grip is offset relative to the sleeve bearing 78 and is approximately centered with the center of gravity of the saw. The arms 91 and 92 also preferably curve or slope upwardly so that the hand grip 93 is higher than the axis of the sleeve bearing 78. The rear handle normally remains with the grip portion 93 approximately horizontal at all times. This is a natural position for the operator so that strain and fatigue are minimized. When the saw is changed from bucking to felling position, the swivel member 80 which carries the rear handle turns in the sleeve bearing 78 or, more accurately, the saw, including the chassis, engine, fuel tank, cutting chain and support and air intake assembly, is turned 90° while the rear handle remains in its normal horizontal position. The carburetor, by reason of its connection with the swivel member 80, also remains in its normal position and is thus kept right side up. Hence, merely by continuing to hold the rear handle in a natural manner as the saw is turned, the operator in effect holds the carburetor against turning and keeps it up-

right. The rotatable mounting of the carburetor permits the relative rotation between the carburetor and the intake manifold 18 which is fixed with respect to the engine.

5 A latch member 94 (Fig. 4) pivotally mounted on a rearwardly extending portion of the swivel member 80 is adapted to engage notches in the indexing plate 18 to hold the swivel member 80 against rotation relative to the sleeve bearing portion 76 of the air intake assembly. A spring-pressed plunger 95 presses upwardly on the rear end of the latch to hold the latch in locked position. The indexing plate 18 normally has two notches, one for felling position and the other for bucking position, although more can be provided if desired. The latch 94 is released by pressure of the operator's thumb on the rear end portion of the latch member which is suitably shaped for this purpose and is sufficiently near the hand grip 93 so that the operator can release the latch without removing his hand from the grip.

20 A throttle control of novel construction is also associated with the rear handle. A plunger 96 is slidable in the tubular hand grip portion 93 against the action of a spring 97 and projects beyond the end of the hand grip. The plunger is held against rotation by a stud 98 working in a slot 99 of such length as to limit the longitudinal movement of the plunger. A small bell crank lever 100 (Fig. 6) is pivoted at 101 on a supporting portion 102 which projects forwardly from the hand grip. One arm of the bell crank is rounded at its end and extends through a slot in the hand grip and into a notch 103 in the plunger 96. The other arm is connected by a wire or rod 104 to the throttle control arm 105 (Fig. 3) of the carburetor. The projecting end of the plunger 96 is partially surrounded by a protecting guard 106. A guard 107 on the hand grip 93 protects the bell crank 100 and also serves as a finger rest to prevent the operator's hand from slipping on the grip. By pressing in on the plunger 96 against the action of spring 97, the operator rotates the bell crank 100 in a clockwise direction and pulls on the connecting wire 104 to open the throttle. In order to hold the throttle open, particularly when starting the engine, the throttle control is provided with a latch which is shown in the form of a plunger 108 (Fig. 4) which is slidable in a hole through the supporting portion 102 on which the bell crank is mounted. When the latch plunger 108 is pushed up—after the throttle control plunger 96 has been pushed in—the end of the latch plunger engages the bell crank 100 to hold it in open-throttle position. The plunger is preferably provided with a notch or abutment which engages the bell crank arm to hold the plunger in locking position. A light spring 109 tends to push the latch plunger downwardly so that it can be released merely by pushing in farther on the throttle control plunger 96 to disengage the bell crank from the latch plunger.

25 60 65 70 75 The rear bracket assembly also includes a rear foot 111 (Figs. 2, 3 and 5) which is approximately L-shaped and, as viewed from the rear, projects downwardly and then to the right from the forward end of the air filter casing 69 and associated bracket portion 73. The foot 111 is to the rear of the center of gravity of the saw and the horizontal portion 112, which is adapted to rest on the ground when the saw is set down, extends transversely of the saw and is approximately

centered with respect to a line extending directly rearwardly from the center of gravity.

With the construction described above, the entire rear bracket assembly, including the air intake and filter, rear handle and rear foot, is removable merely by removing the two bolts 14. This also releases the carburetor which is held between the air intake assembly and the intake manifold. Assembly and disassembly of the saw is thus extremely simple.

The saw is provided with a front handle 114 comprising a tubular member which is attached to the chassis at one end by bolts 115 and has an upwardly extending portion 116, a top handle portion 117 which extends across above the front portion of the fuel tank and is substantially horizontal, a side handle portion 118 (Fig. 2) which extends downwardly on the left hand side of the fly wheel housing when the saw is in bucking position and a front foot portion 119 which extends across underneath the saw and is attached to the chassis at its right hand end by one or more bolts 120 (Fig. 3). The top handle portion 117 curves smoothly into the side handle portion 118 so that the operator's hand can slide from one portion to the other without impediment. The top handle portion 117 and the major portion of the side handle 118 lie approximately in a vertical plane passing through the center of gravity of the saw. With this arrangement, the saw can be held or carried by the front handle alone without tipping objectionably. The lower portion of the side handle 118 extends forwardly, as seen in Fig. 2, so that the front foot portion 119 is located substantially in front of the center of gravity of the saw. As the front foot portion is a continuation of the side handle portion 118 and is of greater length than the width of the saw, the front foot, in conjunction with the rear foot 111 described above, provides a firm and stable support for the saw when it is set on the ground.

The arrangement of the front handle 114 and rear handle 90 greatly facilitates the handling and manipulation of the saw. The operator's hands are at all times in a natural and unstrained position. When the saw is in the bucking position illustrated in the drawings, it is held by the top handle portion 117 and the rear handle 90 which are both substantially horizontal and parallel to one another. The saw can be tilted forward or back by raising or lowering one hand or the other. To tilt the saw sideways, the operator can shift his hand in one direction or the other along the top handle portion 117 so that the weight of the saw tilts it naturally. In the felling position, the saw is held by the side handle portion 118 and rear handle 90 which has been turned relative to the chassis so that it is still horizontal and now substantially parallel to the side handle portion 118. The operator's hands are thus in the same natural position during both bucking and felling.

A lubricating oil tank 122 is mounted on the right hand side of the fuel tank 14 and is curved to conform to the curved upper surface of the fuel tank. The lubricating oil tank has a filler cap 123 and also an opening to receive a pump assembly 124 which is mounted on a cover plate 125 for the opening. The cover plate is removable held in place by a plurality of screws 126. The pump has a spring-pressed operating plunger 127 which projects upwardly from the cover plate in proximity to the front handle 114. A flexible tube 128 connects with the discharge out-

let 129 of the pump and extends to a passageway leading to the sprocket wheel for driving the cutting chain 3. Downward pressure on the plunger 127 forces a small quantity of oil through the tube 128 and connecting passageways to the driving sprocket from which it is thrown by centrifugal force on to the cutting chain. The location of the plunger 127 makes it possible for the operator to supply lubricant to the chain without removing his hand from the handle.

The operation of the saw is extremely simple and will be readily understood from the foregoing description. With the saw resting on the front foot 119 and rear foot 111, the engine is started by means of the starting handle 10. During the cranking of the engine, the choke valve 53 is normally closed and the throttle is held open by the latch plunger 108. When the engine has been started, the choke valve is opened and the latch 108 is released. Engine speed is controlled by the operator's right thumb pressing on the throttle control plunger 96.

If the saw is to be used in the bucking position, it is picked up by the rear handle 90 and top handle portion 117 of the front handle 114. With the saw held in proper position to begin a cut, the operator speeds up the engine by pushing in on throttle control plunger 96 with his right thumb. When a predetermined engine speed is attained, the automatic clutch engages to drive the cutting chain and the operator proceeds with the cut. By causing the teeth 13 to engage the log and then lifting up on the rear handle, the operator can swing the chain support down about the teeth 13 as a fulcrum and thereby feed the cutting chain into the wood. It will be noted that the operator's hands remain in a natural position, no twisting or other unnatural movement being required to control the throttle. When the cut has been completed, the operator releases the throttle plunger 96, whereupon the engine slows down to idling speed and the automatic clutch disengages the cutting chain from the engine.

When it is desired to use the saw in felling position, the operator releases the latch 94 by pressing down on it with his thumb without removing his hand from the rear handle. He then turns the saw by means of the front handle, for example by sliding his right hand along the handle from the top portion 117 to the side handle portion 118 while continuing to hold the rear handle in the same position. When the saw has been turned 90°, the latch 94 engages in another notch in the indexing plate 78 to lock the rear handle with respect to the chassis of the saw. The operator's hands are in the same natural position during the felling operation as during bucking and the sequence of operations in making a cut is substantially the same as described above.

The novel construction and arrangement of the fuel system as described above assures uniform supply of fuel to the engine not only in normal bucking and felling positions of the saw but also when the saw is tilted at a substantial angle, for example an angle of 30° from the normal positions. Moreover, the simple operation of turning the saw from one position to the other as described above automatically turns the carburetor relative to the saw so that the carburetor remains right side up at all times.

Another embodiment of the invention is shown in Figs. 7, 8 and 9. Except for the differences shown in the drawings and pointed out below, this embodiment is essentially the same as that

illustrated in Figs. 1 to 6 and corresponding parts are designated by the same reference numerals with the addition of 200.

The chain saw shown in Figs. 7, 8 and 9 has a chassis 201 on which is mounted a chain support 202 for the cutting chain 203. A one-cylinder engine 204 having a cylinder 205 and spark plug 206 is mounted with its cylinder inclined, preferably at about 45° to the horizontal (Fig. 7). The crank shaft of the engine carries a fly wheel and fan enclosed in a housing 209 and a cable-type starter having a starting handle 210 (Fig. 9). Power is transmitted from the engine to the cutting chain by a transmission enclosed in a housing 212 with which is associated a series of points 213 adapted to engage the work and act as fulcrum for the saw.

The fuel system comprises a fuel tank 214, a carburetor 215 connected to the tank by flexible tubing 216, an air intake assembly 217 and an intake manifold 218. The fuel tank 214 comprises an upper main chamber 220 and a lower auxiliary chamber 221. The tank has side walls 222 and 223, an arcuate outer or upper wall 224 and a lower wall 225 comprising an inclined portion 226 which overlies the engine, a downwardly extending portion 227 and a rearwardly extending portion 228. The two chambers 220 and 221 are partially separated by a partition or baffle 230 but communicate with one another through an opening 231 between the left hand end of the partition 230 and the left hand wall 222 of the fuel tank (Fig. 8). The lower chamber 221 is divided by a partition or baffle 232 into two compartments 233 and 234 which communicate with one another through an opening 235 between the rear edge of the partition 232 and the outer wall 224 of the fuel tank (Fig. 7). The fuel tank has an outlet opening 236 provided with a suitable shut-off valve and connected by the flexible tubing 216 to the carburetor. A filling opening 237 is surrounded by a downwardly projecting skirt 238 and provided with a removable liquid-tight and airtight filler cap 239. The venting system is similar to that described above and comprises vent cups 241 and 242 having vent holes 243 and 244, respectively. A vent tube 245 extends rearwardly and towards the left from the vent cup 241 and terminates at 246 near the vent cup 242. A second vent tube 247 extends upwardly, forwardly and to the right from the vent cup 242 and terminates at 248 adjacent the vent cup 241.

The carburetor 215, including an extension collar 256, is rotatably supported between an annular shoulder 264 on the intake manifold 218 and an axially aligned bearing portion of the air intake assembly 217, as described above. The air intake assembly 217 includes a filter unit 268 having a cylindrical casing 269 and a cylindrical filter unit 270 mounted inside the casing with an annular air passage 271 between the casing and the filter. The inner surface of the filter is cleaned by a rotatable and reciprocable brush 272. The assembly is mounted on a chassis by means of a bracket portion 273 and bolts 274. An air passageway 275 leads from the annular space 271 to the interior of a sleeve-bearing portion 276 which is open at both ends and in axial alignment with the annular shoulder 264 of the intake manifold. A bearing bushing 277 fits inside the sleeve portion 276 and a fixed indexing plate 278 is provided on the rear end face of the sleeve portion.

A swivel member 280 is rotatable inside the bearing bushing 277 and has an annular flange 75

281 engaging the indexing plate 278. An annular swivel plate 282 which is secured to the forward end of member 280 bears on the front end of the bearing portion 276 and thus cooperates with flange 281 to hold the swivel 280 against axial movement. The carburetor is mounted between this swivel member 280 and the aligned end portion of intake manifold 218 by means of rubber rings, as described above. 10 Cup-shaped ears 286 on the swivel plate 282 loosely embrace corresponding protuberances on the carburetor to hold the carburetor against radial displacement and to cause it to turn with the swivel member. A passageway 288 in the 15 swivel member 280 provides communication for the flow of air from the passageway 275 of the filter to the carburetor.

The rotatable member 280 carries a rear handle 290 comprising upwardly curved arm portions 292 and a tubular handgrip portion 293 extending across between the rear ends of the arms. A spring-pressed latch member 294 engages notches in the indexing plate 278 to hold the swivel member 280, and hence the rear 25 handle, in selected position. The rear handle carries a spring-pressed throttle control plunger 296 connected by suitable means with the throttle control arm 305 of the carburetor, as described above, so that the operator can control 30 the carburetor by thumb pressure on the plunger 296 without removing his hand from, or changing his grip on, the rear handle portion 293.

The air intake assembly is also provided with 35 a rear foot portion 311 which projects downwardly from the bearing portion 276 and has a horizontal portion 312 extending transversely of the saw.

The saw has a front handle 314 comprising a 40 tubular member attached to the chassis at one end by bolts 315 and having an upwardly extending portion 316, top handle portion 317, side handle portion 318 and a front foot portion 319 which extends across beneath the saw and is attached to the chassis at its right hand end. 45 The saw is preferably provided with a chain lubricating system like that described in conjunction with the embodiment of Figs. 1 to 6. To simplify the drawings, this lubricating system has been omitted from Figs. 7, 8 and 9.

The arrangement and shape of the parts shown in Figs. 7, 8 and 9 provide still greater compactness and lighter weight. The operation of the saw is essentially the same as described 55 above in connection with Figs. 1 to 6.

While the invention has been described with particular reference to the preferred embodiments illustrated in the drawings, it will be understood that the novel features of the invention 60 are applicable to other embodiments and in no way limited to the specific constructions herein shown and described. Moreover, while best results are attained by the cooperation of all of the novel features shown and described, it will 65 be understood that certain of the features may, if desired, be used separately from others. Moreover, the several features of the chain saw shown in Figs. 7 to 9 may be interchanged with those of the saw shown in Figs. 1 to 6. References 70 in the foregoing description to "left" and "right" are used for convenience in describing the particular constructions shown in the drawings and are not to be construed to limit the invention. While the angularity of the fuel 75 tank shown in Fig. 7 is not as great as that

shown in Fig. 4, the upper and lower portions of the tank being disposed at an obtuse angle to one another, the term "substantially L-shaped" as herein used is understood to comprise both embodiments as well as similar arrangements.

What we claim and desire to secure by Letters Patent is:

1. In a chain saw driven by an internal combustion engine, the combination of a fuel tank which is substantially L-shaped in vertical longitudinal section, comprising a horizontal portion and a downwardly projecting portion at one end of said horizontal portion, an intake manifold and an air intake passage below the fuel tank, a carburetor swivelly mounted between the intake manifold and the air intake passage, a flexible connection from the carburetor to the downwardly projecting portion of the L-shaped fuel tank and a pair of handles comprising a fixed front handle and a swivelly mounted rear handle connected with the carburetor, whereby rotation of the rear handle rotates the carburetor.

2. In a chain saw driven by an internal combustion engine and having a frame and saw chain support, the combination of a fuel tank which is substantially L-shaped in vertical fore-and-aft section comprising a horizontal portion and a downwardly projecting portion at the rear end of the horizontal portion, an intake manifold and an air intake passage below the fuel tank and in fixed position relative to the frame, a carburetor swivelly mounted between the intake manifold and the air intake passage, a flexible fuel conduit connecting the carburetor with the downwardly projecting portion of the fuel tank and a handle swivelly mounted on the air intake passage and connected with the carburetor, whereby the carburetor turns with the handle.

3. In a chain saw driven by an internal combustion engine and having a frame and a saw chain support in fixed relation to the frame, the combination of a fuel tank which is substantially arcuate in vertical longitudinal section comprising a portion disposed above the engine and a downwardly projecting portion at the rear of the engine, an intake manifold and an air intake passage mounted below the fuel tank in fixed relation to the frame and having axially aligned openings, a carburetor swivelly mounted in said openings, a flexible conduit connecting the carburetor with the downwardly projecting portion of the fuel tank and a saw supporting handle swivelly mounted on the air intake passage to turn about the axis of said openings, said handle being connected with the carburetor, whereby the carburetor turns with the handle relative to the frame.

4. In a chain saw driven by an internal combustion engine and having a chassis and a saw chain support fixed relative to the frame, the combination of a fuel tank which fits over the engine and is substantially L-shaped in vertical longitudinal section comprising an approximately semicircular upper wall and a lower wall having a horizontal portion joining the upper wall at one end, a downwardly extending portion at the opposite end of the horizontal portion and a second horizontal portion joining the lower end of the downwardly extending portion and the opposite end of the upper wall to form a downwardly extending portion of the tank, a carburetor swivelly mounted on the chassis below the

fuel tank, a flexible fuel conduit connecting the carburetor with the downwardly extending portion of the fuel tank and a saw supporting handle swivelly mounted on the chassis and connected with the carburetor, whereby the carburetor turns with the handle relative to the chassis.

5. In a chain saw driven by an internal combustion engine and having a chassis and a saw chain support in fixed relation to the chassis, the combination of a fuel tank which is substantially L-shaped in vertical longitudinal section comprising a horizontal portion above the engine and a downwardly projecting portion, a baffle partially separating said portions of the tank but leaving an opening between them adjacent one side of the tank, a carburetor swivelly mounted on the chassis below the fuel tank, a flexible conduit connecting the carburetor with the downwardly projecting portion of the fuel tank, and a saw supporting handle swivelly supported on the chassis and connected with the carburetor, whereby the carburetor turns with the handle.

6. In a chain saw driven by an internal combustion engine and having a chassis, the combination of a fuel tank which is substantially arcuate in vertical longitudinal section comprising an upper portion overlying the engine and a lower portion projecting downwardly at the rear of the engine, a baffle substantially separating said portions of the tank and leaving an opening between them only at one side of the tank, a second baffle dividing said lower portion into a larger chamber at the side adjacent said opening and a smaller chamber at the opposite side of the tank, said chambers being connected by an opening adjacent the outside rear wall of the tank, a carburetor swivelly mounted on the chassis below the fuel tank, a flexible conduit connecting the carburetor with the bottom of said smaller chamber, and a saw supporting handle swivelly supported on the chassis and connected with the carburetor, whereby the carburetor turns with the handle.

7. In a chain saw driven by an internal combustion engine and having a chassis, the combination of a fuel tank which fits over the engine and is substantially L-shaped in vertical longitudinal section comprising an arcuate upper wall and a lower wall fitting over the engine and providing an upper main chamber and a downwardly projecting lower chamber, a pair of vent storage cups provided on the upper wall, one of said cups being located on the forward upper portion of said wall adjacent one side of the tank and the other being located on the rearward upper portion of said wall adjacent the opposite side of the tank, a vent opening connecting each of the cups to the atmosphere, a vent tube connected with each of the cups and opening on the inside of the tank adjacent the other cup of the pair, a carburetor swivelly mounted on the chassis below the fuel tank, a fuel line connecting the carburetor with the lower chamber of the fuel tank, and a saw supporting handle swivelly supported on the chassis and connected with the carburetor, whereby the carburetor turns with the handle.

8. In a chain saw driven by an internal combustion engine and having a chassis, the combination of a fuel tank which is substantially L-shaped in vertical section comprising an upper chamber overlying the engine and a downwardly projecting lower chamber, an intake manifold having a circular opening, an air intake passage having an opening in axial alignment with that

of the intake manifold, a rubber ring surrounding each of said openings, a carburetor disposed between said rubber rings, means for securing the air intake passage to the chassis to clamp the carburetor between said rubber rings and resiliently support it for rotation about the axis of said holes, a fuel line connecting the carburetor with the lower chamber of the fuel tank and a saw supporting handle swively supported by the air intake passage to turn about said axis and connected with the carburetor, whereby the carburetor turns with the handle.

9. In a chain saw driven by an internal combustion engine and having a chassis, the combination of a fuel tank mounted over the engine, an intake manifold having an opening, an air intake unit comprising an air filter and an air passage terminating in a cylindrical bearing in axial alignment with the opening of the intake manifold, means for securing the air intake unit to the chassis, a carburetor swively supported between said cylindrical bearing and the opening of the intake manifold, a fuel line connecting the carburetor with the fuel tank, a handle support rotatable in said cylindrical bearing, a saw supporting handle carried by said support and means connecting the handle support with the carburetor, whereby the carburetor turns with the handle support and handle.

10. In a chain saw driven by an internal combustion engine and having a chassis, the combination of a fuel tank mounted over the engine, an intake manifold having an opening below the fuel tank, a bearing fixedly supported on the chassis in alignment with said opening, a carburetor swively supported between the bearing and the opening, a fuel line connecting the carburetor with the fuel tank, a handle support rotatable in said bearing, said support extending rearwardly and upwardly from said bearing and terminating in a bifurcated portion, a handle extending across between the ends of the bifurcated portion of the support and means connecting the handle support with the carburetor, whereby the carburetor turns with the handle support and handle.

11. In a chain saw driven by an internal combustion engine and having a chassis, the combination of a fuel tank mounted over the engine, an intake manifold having an opening below the fuel tank, a bearing fixedly supported on the chassis in alignment with said opening, a carburetor swively supported between the bearing and the opening, a fuel line connecting the carburetor with the fuel tank, a handle support rotatable in said bearing, a saw supporting handle carried by said support, means connecting the handle support with the carburetor whereby the carburetor turns with the handle support and handle and a latch for releasably holding the handle and carburetor in any of a plurality of predetermined positions.

12. In a chain saw driven by an internal combustion engine and having a chassis, the combination of a fuel tank mounted over the engine, an intake manifold having an opening below the fuel tank, a bearing fixedly supported on the chassis in alignment with said opening, a carburetor swively supported between the bearing and opening and having a throttle, a handle support rotatable in said bearing, said support extending rearwardly from the bearing and terminating in a bifurcated portion, a handle extending across between the ends of the bifurcated portion of the handle support, a throttle control member movably mounted at one end of the handle, being

movable in a direction lengthwise of the handle, connections between the control member and the throttle and means connecting the handle support with the carburetor, whereby the carburetor turns with the handle support and handle.

13. In a chain saw driven by an internal combustion engine and having a chassis and a carburetor, the combination of a fuel tank which is substantially L-shaped in vertical fore-and-aft section comprising an upper chamber and a lower chamber communicating with the upper chamber adjacent the left hand side of the tank as viewed from the rear with the saw in bucking position, an intake manifold having a rearwardly facing opening below the fuel tank, a bearing fixedly supported on the chassis directly to the rear of and in alignment with said opening, a fuel line connecting the carburetor with the lower right hand portion of the lower chamber of the fuel tank, a substantially rectangular front handle comprising a tubular member secured at one end to the upper right hand side of the chassis, and extending upwardly, across the top of the chassis, downwardly on the left hand side of the chassis, across below the chassis and secured at the other end to the lower right hand side of the chassis, the upper and left hand portions of the handle being approximately in a vertical plane passing through the center of gravity of the saw while the lower portion is forward of said plane, a rear handle support rotatable in said bearing, a rear handle carried by said support and having a hand grip portion which is approximately parallel with the upper portion of the front handle when the saw is in bucking position and—by rotation of said rear handle support—is approximately parallel with the left hand portion of the front handle when the saw is in felling position and means connecting the rear handle support with the carburetor whereby the carburetor turns with the rear handle and is in upright position in both of said positions of the saw.

14. In a chain saw driven by an internal combustion engine and having a chassis, the combination of a fuel tank mounted over the engine, an intake manifold having a rearwardly facing opening below the fuel tank, a bearing fixedly supported on the chassis directly to the rear of and in alignment with said opening, a carburetor swively supported between the bearing and the opening, a fuel line connecting the carburetor with the fuel tank, a front handle comprising a tubular member secured at its ends to the chassis and having a top portion extending across above the chassis when the saw is in bucking position, a side portion at approximately right angles to the top portion and a foot portion below the chassis and approximately parallel to the top portions, the top portion and side portion being approximately in a vertical plane passing through the center of gravity of the saw while the foot portion is forward of said plane, a rear handle rotatably supported by said bearing and having a hand grip portion which is approximately parallel with the top portion of the front handle when the saw is in bucking position and—by rotation of the rear handle in said bearing—is approximately parallel with the side portion of the front handle when the saw is in felling position and means connecting the rear handle with the carburetor whereby the carburetor turns with the rear handle and is in upright position in both of said positions of the saw.

15. In a chain saw driven by an internal combustion engine having a carburetor, said chain

17

saw having a chassis and a saw chain support in fixed relation to the chassis, a fuel tank which is substantially L-shaped in vertical longitudinal section and comprises an upper main chamber overlying the engine and a lower auxiliary chamber separated from the upper chamber by a wall with an opening connecting the two chambers adjacent one side of the tank, a fuel outlet located at the bottom of the lower chamber at the opposite side of the tank, the carburetor being disposed below the fuel tank and on the same side as said outlet, and a fuel line connecting the carburetor with said outlet of the fuel tank.

16. In a chain saw driven by internal combustion engine having a carburetor, said chain saw having a chassis and a saw chain support rigidly fixed to the chassis, a fuel tank which is substantially L-shaped in vertical section and comprises an upper main chamber overlying the engine, a lower auxiliary chamber projecting downwardly from the main chamber, a baffle separating the two chambers except for an opening adjacent one side of the fuel tank and a second baffle disposed at approximately right angles to the first and dividing the lower chamber into a larger compartment communicating through said opening with the upper chamber and a smaller compartment out of direct communication with the upper chamber but communicating with the larger compartment through an opening adjacent the outside wall of the fuel tank, an outlet located at the bottom of the smaller compartment of the lower chamber in spaced relation to the opening connecting the smaller compartment with the larger compartment, the carburetor being disposed below the fuel tank and on the same side as said outlet and a fuel line connecting the carburetor with said outlet of the fuel tank.

17. In a chain saw driven by an internal combustion engine having a carburetor, a fuel tank comprising side walls, an approximately semicircular outer wall joined at its side edges to the side walls, a stepped bottom wall joined at its side edges to the side walls and its ends to the outer wall, the bottom wall having an upper level cooperating with the side walls and outer wall to form an upper fuel chamber and a downwardly extending portion cooperating with the side walls and outer wall to form a lower fuel chamber, and a partition partially separating said chambers but with an opening connecting them adjacent one of the side walls, the carburetor being disposed below the fuel tank and at the side opposite said opening and a fuel line connecting the carburetor with the lower portion of the lower chamber on the same side as the carburetor.

18. In a chain saw driven by an internal combustion engine having a carburetor, an L-shaped fuel tank comprising side walls, an approximately semicircular outer wall, a stepped bottom wall having an upper fuel chamber and a downwardly projecting portion cooperating with the side walls and outer wall to form a lower fuel chamber, a partition separating the said chambers except for an opening between them adjacent one of the side walls and a second partition which is approximately perpendicular to said first partition and divides the lower chamber into a larger compartment at the side adjacent said opening and a smaller compartment at the opposite side of the tank, said compartments being connected by an opening adjacent the outside wall of the tank, a fuel outlet located at

18

the bottom of the smaller compartment and spaced from the last mentioned opening, the carburetor being disposed below the fuel tank and on the same side as said outlet and a fuel line connecting said outlet with the carburetor.

19. In a chain saw driven by an internal combustion engine having a carburetor, an L-shaped fuel tank comprising side walls, an approximately semicircular outer wall and a stepped bottom wall, a pair of vent cups provided on the outer wall, one of the cups being located on the forward upper part of said outer wall adjacent one of the side walls and the other of the cups being located on the rearward upper portion of said outer wall adjacent the opposite side wall, a vent opening connecting each of said cups with the atmosphere, a vent tube for each of said cups, each tube being connected at one end to its respective cup and having the other end open to the interior of the tank adjacent the other cup of the pair, the carburetor being disposed below the fuel tank and a fuel line connecting the carburetor with the fuel tank.

20. In a chain saw driven by an internal combustion engine and having a chassis and a saw chain support fixed relative to the chassis, the combination of an L-shaped fuel tank comprising side walls, an approximately semicircular outer wall, a stepped bottom wall having an upper level cooperating with the side walls and outer wall to form an upper fuel chamber and a downwardly extending portion cooperating with the side walls and outer wall to form a lower fuel chamber below and at the rear of the upper chamber, a partition separating said chambers except for an opening between them adjacent the left hand side wall of the tank as viewed from the rear of the saw, and a second partition which is approximately perpendicular to the first mentioned partition and divided the lower chamber into a larger compartment at the side adjacent said opening and a smaller compartment at the opposite side of the tank, said compartments communicating with one another through an opening adjacent the rear portion of the outer wall, a fuel outlet located at the bottom of the smaller compartment and spaced from the last mentioned opening, a fuel inlet opening at the top of the tank, an airtight closure for said inlet opening, a vent cup provided on the upper forward portion of the tank adjacent the right hand side wall, a second vent cup provided on the upper rearward portion of the tank adjacent the left hand side wall, a vent opening connecting each of said cups with the atmosphere, a vent tube for each of said cups, each tube being connected at one end to its respective cup and having the other end open to the interior of the tank adjacent the other cup, an intake manifold having an opening below the fuel tank and on the same side as said fuel outlet, an air intake unit comprising an air filter and an air passage opening at one end into the air filter and provided at the other end with a cylindrical bearing portion disposed directly to the rear of and in axial alignment with the opening of the intake manifold, a carburetor swivelly supported between said bearing and the opening of the intake manifold, a fuel line connecting the carburetor with the outlet of the fuel tank, a front handle comprising a tubular member secured at its ends to the right hand portion of the chassis and having a top portion extending across above the chassis when the saw is in bucking position, a left side portion at approximately right angles

to the top portion and a foot portion below the chassis and approximately parallel to the top portion, the top portion and left side portion being approximately in a vertical plane passing through the center of gravity of the saw while the foot portion is forward of said plane, a rear foot portion projecting downwardly from said air intake unit, a rear handle rotatably supported by the cylindrical bearing portion of the air intake passage and having a hand grip portion which is approximately parallel with the top portion of the front handle when the saw is in bucking position—by rotation of the rear handle in said bearing—is approximately parallel with the side portion of the front handle when the saw is in felling position, and means connecting the rear handle with the carburetor whereby the carburetor turns with the rear handle and is in upright position in both of said positions of the saw.

21. In a chain saw driven by an internal combustion engine and having a chassis, a saw chain support in fixed relation to the chassis, a fuel tank mounted in fixed relation to the chassis, a saw-supporting handle fixedly mounted on the chassis, a second saw-supporting handle rotatably mounted on the chassis for rotation about an approximately horizontal axis, a carburetor rotatably mounted on the chassis for rotation about an approximately horizontal axis, fluid conduits connecting the carburetor with the fuel tank and the engine, said conduits permitting

at least limited rotation of the carburetor relative to the chassis, and connections between the carburetor and said rotatable saw-supporting handle, whereby the carburetor turns with the handle relative to the chassis.
